UNITED STATES PATENT OFFICE

2,562,877

DAYLIGHT LOADING ROLL FILM
DEVELOPING TANK

Albert W. Balluff, Chicago, Ill.

Application May 12, 1948, Serial No. 26,593

5 Claims. (Cl. 95—90.5)

1

My invention relates to an improved daylight loading roll film developing tank.

Attempts have heretofore been made to construct a complete roll film developing tank capable of receiving a roll of ordinary roll camera film and developing that film without the use of a darkroom or light-tight changing bag. However, such devices have not been practical for use by average persons because they depend on complicated and expensive mechanisms and require expert manipulation. For this reason, the film developing tanks that have enjoyed substantial use have been of the type requiring a darkroom or light-tight changing bag for loading.

It is, accordingly, a general object of the present invention to provide an improved daylight loading roll film developing tank suitable for use by the average person.

A more specific object of the present invention is to provide an improved daylight loading roll film developing tank which may be manipulated in a manner similar to a roll film camera, to the end that the average camera user will have the skills requisite to the operation of the device.

Still another object of the present invention is to provide an improved daylight loading roll film developing tank having loading mechanism similar to the loading mechanism of a conventional camera.

Another object of the present invention is to provide an improved daylight loading roll film developing tank having integral means to separate the film from the backing portion thereof.

My invention further resides in providing an improved daylight loading roll film developing tank having features of construction, combination, and arrangement rendering it simple in construction and reliable in operation to the end that a rugged structure of minimum expense having maximum utility is provided.

The novel features which I believe to be characteristic of my invention are set forth with particularity in the appended claims. My invention, itself, however, both as to its organization and method of operation, together with further objects and advantages thereof, may best be understood by reference to the following description taken in connection with the accompanying drawing in which:

Figure 1 is a side elevational view of a roll film developing tank constructed in accordance with the features of the present invention;

Figure 2 is a cross sectional view through the axis 2—2, Figure 1, showing the tank in the loading condition;

2

Figure 3 is a view like Figure 2 but showing the tank in the developing condition;

Figure 4 is a cross sectional view through the axis 4—4, Figure 3; and

Figure 5 is an enlarged fragmentary view showing how the film is cut from the backing.

Figure 6 is a fragmentary cross sectional view through the axis 6—6, Figure 4;

Figure 7 is a fragmentary top plan view of the cup-shaped knob receiving portion of the structure of Figure 1 and showing the indexing keyways formed therein.

Referring to Figure 1, there is shown a housing adapted to receive roll film. This housing includes a receptacle portion R defined by spaced circular top and bottom members 10 and 12 and by the substantially cylindrical side wall 14. A closure, shown generally at C, is shiftably mounted on one side of the receptacle R.

20 The purpose of the receptacle R is to provide a space or cavity 74 for developing the roll film whereas the purpose of the closure C is to provide mechanism to insert the film in the receptacle R without exposing the same to light.

25 A pair of flanges 11 and 13, Figure 1, are received within the receptacle R and are mounted on the hollow central shaft 15 to define a film receiving spool.

As is best seen in Figures 2 and 3, the top and bottom flanges 11 and 13 of the spool each have spiral grooves adapted to receive the film and to guide the same into spaced convolutions suitable for developing. In the view of Figure 3, the film 18 is shown in the coiled position having spaced convolutions in accord with the shape of the grooves of flanges 11 and 13.

The spool defined by flanges 11 and 13 is held centrally of the cavity of receptacle R by the protuberance 12^a in bottom member 12 which rides in a suitable notch in flange 11 and by the rod 17 which passes through a suitable opening in upper member 10 and is received in the hollow interior of shaft 15.

45 The cylindrical side wall 14 has a lengthy film receiving slot 22 at one portion thereof. This slot is seen in top view in Figure 3 and side view at the broken away portion of Figure 4. This slot is of sufficient length and width to receive the film portion of a roll film without binding or tearing.

As indicated in Figures 2 and 3, the closure C defines two spaced roll film receiving cavities 24 and 26. Each of these cavities is of substantially cylindrical shape and is adapted to receive a roll film in the same fashion as a conventional

camera. A backing panel 28 extends across the closure C and is held against the walls thereof by snap clips 30 which coact with buttons 32 located in walls 34 and 36.

The cavities 24 and 26 each have central rotatable film receiving posts at each end to engage the spools upon which the film is wound. These posts are indicated at 25 and 27 respectively, Figure 2, where they may be viewed through the hollow central portions of the spools. Similar posts are provided at the top end of the cavities 24 and 26, as shown in the broken away portion of Figure 1 where a post 25 is shown in engagement with a film receiving spool 50. The upper posts 25 and 27 extend through the top of cavities 24 and 26 respectively and form knobs 52 which may be rotated to wind the film from one cavity to the other.

The closure C defines a concave surface which snugly fits against the surface of the side wall 14 of receptacle R. This surface is formed by the wall portions 42 and 44. The guides 46 and 48 overlay the lips 42 and 44 respectively to hold the closure C in mating engagement with the side wall 14 of receptacle R and to limit the shifting movements of closure C relative to receptacle R.

A gate 54 automatically closes and opens the slot 22 in accord with the position of closure C relative to receptacle R. As will be evident from the views of Figures 2 and 3, the gate 54 is of arcuate cross section and has its face curved for snug mating engagement with the curved side wall 14 of the receptacle R. A panel of rubber or similar yielding material, 55, covers the face of gate 54 to provide a fluid tight engagement. Moreover, as shown in the broken away portion of Figure 4 and in Figure 6, the gate 54 extends beyond the length of the slot 22 to provide a complete seal when in the closed position.

Opening and closing movements of gate 54 are guided by the guide channel defined by the upper and lower guide pieces 56 and 58 and by the curved lip portion of the sheet metal plate 60. The guide pieces are of identical construction and are positioned to engage the top and bottom of the gate 54. Moreover, as shown in Figure 2, they engage the back or outer face of the gate 54 to limit opening movements thereof.

The curved metal plate 60 is attached at its upper and lower ends to the guide pieces 56 and 58. It extends beyond the edges of these pieces, as shown in Figure 2, to define a space to receive gate 54. The front portion of gate 54 is engaged by the wedge 84, Figure 6, to swing the gate to open position and avoid catching of the edge of the gate against the end of the metal plate 60. If desired, a wedge may be attached to member 82, Figure 4, to supplement the action of wedge 84 in defining a cam surface to guide gate 54 into the channel defined by member 60.

A bar 62 is formed on the side portion 14 of receptacle R and defines a wall against which gate 54 bottoms. In addition, this bar receives the pin 63, Figure 6, which also receives gate 54 to define a hinge. A like pin is provided at the upper end of bar 62 to hinge the upper end of gate 54.

If desired, springs (not shown) may be provided to urge gate 54 to the closed position. Thus, when the closure C is shifted from the closed position of Figure 3 to the open position of Figure 2, the gate 54 swings open as the wedge 84 engages the edge thereof to guide the latter in opening movements in the channel defined by guides 56 and 58 and the metal piece 60.

A metal sheet 76 is supported from upper and lower members 78 and 80, Figure 2, to define a channel in conjunction with sheet 60. This channel guides the film portion through slot 22.

As shown best in Figures 2 and 3, the metal piece 60 is bent back upon itself to define a knife edge 64. This knife is shown in side elevation in Figure 4.

It is the purpose of the knife 64 to cut the film portion from the backing portion of the roll film as it is wound from cavity 24 to cavity 26. This action is best seen in the greatly enlarged cross sectional view of Figure 5 where the backing portion of the film is indicated at 66, the film portion at 68, and the binder tape indicated at 70. As the film progresses, the knife 64 rides between binder tape 70 and the backing portion 66 and thus separates these portions of the film. Since the binder tape 70 is normally attached only to the leading edge of the film as it is wound in the camera, the knife 64 is required to separate that tape only along the trailing edge of the film as indicated in Figure 5.

As seen best in Figure 2, the knife 64 bears against the film as it is wound from cavity 24 to cavity 26.

As the backing portion 66 of the film is wound in cavity 26, the film portion 68 thereof travels through slot 22 and into the cavity defined by receptacle R.

The rod 17 terminates in a handle or knob portion 17a which protrudes from the funnel 72 as shown in Figure 1. At its bottom end this rod is keyed to the shaft 15 to cause rotation of that shaft and the flanges 11 and 13 upon rotation of the knob 17a.

When the backing 66 of the film is entirely wound into the cavity 26, the handle 17a may be rotated to wind the end of the film portion 40 into the film developing cavity 74 as shown in Figure 3. This action results from the frictional engagements between the flanges 11 and 13 and the film which cause the film to follow the movements of the spool defined by these flanges and the shaft 15.

The closure C may then be shifted to the position of Figure 3 to close gate 54 to seal the cavity 74. The film 68 is then in a sealed cavity in condition for development.

The film development tank is preferably provided with light tight means to introduce developing fluids into cavity 74. Such means are well known to the art and may, for example, include a centrally disposed funnel 72 having a tortuous light-tight channel (not shown) communicating with cavity 74.

In accordance with a further feature of the present invention, the spool defined by flanges 11 and 13 is keyed to a predetermined position 60 relative to the slot 22 when it is desired to load film. This position corresponds to that shown in Figure 2 where the grooves on the flanges 11 and 13 are in position to receive the film portion of the film immediately adjacent the slot 22. 65 In other words, the spiral defined by the grooves in these flanges has its open end adjacent the slot 22.

This indexing action is accomplished by the cooperating keyways formed on the cupped surface 70 face of the funnel 72 in which the knob 17a rides and the mating keys formed on the lower surface of the knob 17a. The keyways are shown at 72a, Figures 1 and 7, and the keys at 17b, Figures 1 and 7. When it is desired to rotate the spool defined by the flanges 11 and 13,

the knob 17a is lifted as shown in Figure 1 to free that knob from the keyways and thereby permit rotation.

In this specification and the appended claims, I have used the term "backing portion" of the film to designate the light-tight backing sheet, usually paper, used in roll film to protect the film from exposure to light while loading. I have used the term "film portion" to designate the transparent portion of the film, usually cellulose acetate, upon which is deposited the light sensitive emulsion. These two portions of the roll film are usually held together by a suitable binder tape 10, as indicated in Figure 5.

It will of course be understood that the various component elements of the receptacle R and the closure C are joined to form light-tight film handling and developing spaces. This may be done by various methods well known in the art such as the snug overlapping lips forming joint 15, Figure 1.

When the gate 54 is in the closed position of Figure 3, the members 56 and 58 exert substantial pressure tending to compress the resilient facing 55, thus forming an effective fluid tight seal against escape of developing fluid from the receptacle R.

While I have shown a particular embodiment of my invention, it will, of course, be understood that I do not wish to be limited thereto since many modifications both in the parts themselves and their cooperative structures may be made without departing from the spirit and scope of my invention. I, of course, contemplate by the appended claims to cover any such modifications as fall within the true spirit and scope of my invention.

What is claimed is:

1. A daylight loading roll film developing tank comprising a receptacle defining a light-tight cavity having a film receiving slot, a gate for said slot mounted for swinging opening and closing movements relative thereto, a closure for said slot mounted for shifting movements relative to said receptacle and adapted to catch the free edge of said gate to open said gate upon predetermined shifting movements in one direction relative to said receptacle, said closure further defining a guide bar to engage the back side of said gate to close said gate upon predetermined shifting movements in the opposite direction relative to said receptacle.

2. A daylight loading roll film developing tank comprising a receptacle defining a light-tight developing cavity having a film receiving opening, a closure defining a light tight space about said opening and shiftably mounted relative to said receptacle, a gate operative to close said opening, said closure having cam surfaces adapted to engage said gate and guide said gate in opening and closing movements as said closure is shifted relative to said receptacle.

3. A daylight loading roll film developing tank comprising a receptacle defining a light-tight cavity having a film receiving slot, a gate for said slot mounted for swinging opening and closing movements relative to said slot, a closure for said slot mounted for shifting movements relative to

said receptacle and defining a light-tight space about said slot, said closure being adapted to receive roll film and having elements to cause travel of said film past said slot, means on said closure adapted to engage the free edge of said gate to open said gate upon predetermined shifting movements of said closure in one direction relative to said receptacle, and means on said closure adapted to engage the back side of said gate to close said gate upon predetermined shifting movements of said closure in the opposite direction relative to said receptacle.

4. A daylight loading roll film developing tank comprising a receptacle defining a light-tight cavity having a film receiving slot, a gate for said slot mounted for swinging opening and closing movements relative thereto, a closure for said slot mounted for shifting movements relative to said receptacle and defining a light-tight space about said slot, said closure being adapted to receive roll film and having elements to cause travel of said film past said slot, means on said closure adapted to engage the free edge of said gate to open said gate upon predetermined shifting movements of said closure in one direction relative to said receptacle, means on said closure adapted to engage the back side of said gate to close said gate upon predetermined shifting movements of said closure in the opposite direction relative to said receptacle, and a knife adapted to engage said film at a point adjacent said slot to cut the film portion of said film from the backing portion thereof to permit said film portion to travel through said slot while said backing portion travels past said slot.

5. A daylight loading roll film developing tank comprising a receptacle defining a light-tight cavity having a film receiving opening, a closure defining a light-tight space about said opening and shiftably mounted relative thereto, a gate adapted to close said opening, means on said closure defining cam surfaces for engagement with said gate to open and close said gate as said closure is shifted relative to said receptacle, means in said closure adapted to receive said film for travel past said opening, a knife adapted to engage said film as it travels past said opening to cut the film portion therefrom, said closure further defining guide elements to direct said film through said slot.
